UNITED STATES PATENT OFFICE.

ALEXANDER E. LITTLE, OF LYNN, MASSACHUSETTS, ASSIGNOR TO A. E. LITTLE & CO., OF SAME PLACE.

DESIGN FOR A HEELPIECE FOR SHOE-FORMS.

SPECIFICATION forming part of Design No. 34,237, dated March 19, 1901.

Application filed February 20, 1901. Serial No. 48,195. Term of patent 14 years.

To all whom it may concern:

Be it known that I, ALEXANDER E. LITTLE, a citizen of the United States, residing at Lynn, in the county of Essex and State of Massachusetts, have invented and produced a new and useful Design for a Heelpiece for a Shoe-Form, of which the following is a description, reference being had to the accompanying drawing, forming a part thereof.

10 The drawing presents a perspective view illustrating my design for a heelpiece for a shoe-form.

The leading feature of my design for a heelpiece for a shoe-form consists of a skeleton 15 body of trapezoidal form having a closed eye within its perimeter and one of its upright sides laterally broadened.

As illustrated in the drawing, the skeleton

body A has one of its upright sides a laterally broadened, the width thereof gradually decreasing toward the base a' and top a^2 , and a closed eye a^x is contained within the perimeter of the body in the angle between the top and the inclined side a^3 .

Having fully described my design, what I claim, and desire to secure by Letters Patent, is—

The design for a heelpiece for a shoe-form, substantially as herein shown and described.

In testimony whereof I have signed my name to this specification in the presence of two subscribing witnesses.

ALEXANDER E. LITTLE.
